UNITED STATES PATENT OFFICE.

ARTHUR O. FREEDMAN, OF NEW HAVEN, CONNECTICUT, ASSIGNOR TO THE ARTHUR CHEMICAL COMPANY, OF NEW HAVEN, CONNECTICUT, A CORPORATION OF CONNECTICUT.

DESIGN FOR A BOTTLE.

47,418.

Specification for Design.

Patented June 8, 1915.

Application filed April 2, 1915. Serial No. 18,832. Term of patent 3½ years.

To all whom it may concern:

Be it known that I, ARTHUR O. FREEDMAN, a citizen of the United States, residing at New Haven, in the county of New Haven and State of Connecticut, have invented a new, original, and ornamental Design for a Bottle, of which the following is a specification, reference being had to the accompanying drawings, forming a part thereof, and in which—

Figure 1 is a side elevation; Fig. 2 an edge

view and Fig. 3 a top view of a bottle embodying my design.

I claim:

The ornamental design for a bottle, substantially as shown.

ARTHUR O. FREEDMAN.

Witnesses:

ELLA C. LYNCH,
ELEANOR TYRRELL.
